[57] **CLAIM**

The ornamental design for a combined paper sheets and aperture fasteners therefor, as shown and described.

DESCRIPTION

FIG. 1 is a top plan view of a combined paper sheets and aperture fasteners therefor showing our new design;

FIG. 2 is a side elevational view as seen from the left of FIG. 1, the undisclosed side being the same in appearance;

FIG. 3 is an end elevational view thereof, the undisclosed end being the same in appearance.

FIG. 4 is a top plan view of a modified form of the design shown in FIG. 1.

The undisclosed bottom of FIGS. 1 and 4 are mirror images of the same configuration as the top plan views. The undisclosed end and side elevational views of FIG. 4 are similar to FIGS. 2 and 3, except for the number and placement of the aperture fasteners, as shown on the left margin of FIG. 4.

FIG. 4.

FIG. 2.

FIG. 1.

FIG. 3.
